CLOSURE FOR BAGS

Floyd F. Henriot, Klamath Falls, Oreg.

Application May 21, 1932, Serial No. 612,794

11 Claims. (Cl. 229—65)

The present invention relates to improvements in closures for bags or the like, and its principal object is to provide a closure of the character described that allows of convenient dispensing 5 of the contents of the bag.

More particularly, my invention has reference to small bags adapted for the handling of tobacco, or the like, and it is one of the objects of my invention to provide a closure that allows 10 "Cellophane" to be used for tobacco bags, the superior qualities of "Cellophane" for this purpose being well-known and the principal problem being to provide a means for allowing the contents of the tobacco bag to be dispensed and 15 the bag to be closed at the end of each dispensing operation.

It is particularly proposed in my invention to provide a closure that is slidable on the open end of the bag and may be clamped thereon so as to 20 air-tightly shut off the contents of the bag, but which may also be used for the purpose of cutting an aperture into the bag so that when the closure member is raised, the tobacco is accessible through the opening.

25 Further objects and advantages of my invention will appear as the specification proceeds.

The preferred form of my invention is illustrated in the accompanying drawing, in which

Figure 1 shows my closure by itself in perspective view;

Figure 2, my closure as applied to a bag in central vertical section;

Figure 3, my closure as applied to a bag in horizontal section, taken on line 3—3 of Figure 2;

35 Figure 4, a side elevation of a bag having my closure attached thereto, the closure being in dispensing position;

Figure 5, a similar view from the opposite side showing the closure in bag-closing position;

40 Figure 6, a side elevation of a modified form; and

Figure 7, a vertical section taken along line 7—7 of Figure 6.

While I have shown only the preferred form 45 of my invention, I wish to have it understood that various changes or modifications may be made within the scope of the claims hereto attached without departing from the spirit of the invention.

50 In its preferred form, as illustrated in Figures 1 to 5, my closure comprises a clasp 1 adapted to surround a bag of "Cellophane" of substantially the form of tobacco bags now on the market, the clasp preferably consisting of two 55 side sections 2 and 3 hinged together as at 4

and adapted to be secured at their free ends by projections 5 adapted to be interlocked with registering recesses 6. When the clasp is assembled around the upper end of a tobacco bag, it slides freely thereon, and in order to effect 60 a perfect closure, I preferably provide a cam member 7, which may be covered with cork or rubber, in one of the two sections of the clasp, the cam member being operable by a handle or bail 8 for urging the two walls of the cellophane bag into intimate contact with one another and with the other section of the clasp. It will be understood that any suitable clamping means 65 may be substituted for the one shown in the drawing and that it may even be possible to dispense with the clamping means altogether if the sections of the clasp are made sufficiently close to form a perfect closure for the bag, while still allowing of sliding motion.

The "Cellophane" bags are preferably manufactured with slots 9 extending into the bag material from the upper edge, the slots being preferably rounded along the bottom edges, as shown at 10. The two sections of the clasp are formed with corresponding recesses 11 and 12, and prongs 13 extend from the edges of the recess 11 and are made to pass through the material of the bag and turned over the margin of the recess 12. The bottom edges of these prongs are sharpened so that when the clasp is made to slide downward 75 on the bag, the two prongs 13 cut slits into the bag material in alignment with the side walls of the slots 9 so that when the clasp is moved beyond the original slots, the prongs will extend the slots 80 into the bag material. The section thus separated 85 by the prongs may be cut against the edge of the recess 11 of the clasp so that the slot, on being extended into the bag material, retains its curved lower edge.

The slots 9, which are provided to extend 90 through the center of the bag, leave two tongues 14 and 15 on opposite sides of the slots, and as these tongues become longer, due to the extension of the slots, their upper ends may be cut off against the sharpened upper edges 16 of the clasp, or the 100 clasp can be tilted and the tongues may be torn along the jagged edges 16', (see Figure 1).

In operation, the bags may be manufactured with the slots 9, or the clasp may be relied on for cutting the slots into the bag material. The clasp 105 may be made in the open form shown in Figure 1 and closed upon the bag during manufacture, or the clasp may be manufactured in final form and the upper end of the bag inserted into the space provided between the two sections of the 110

clasp. As the clasp is made to descend on the upper end of the bag, the prongs 13 cut into the bag material to provide the slots 9 as far as the same have not been originally provided.

5 To effect a tight closure of the bag, the clasps are moved downward sufficiently far to make the edges of the recesses 11 and 12 register with the lower ends of the slots 9, whereupon the bail 8 may be swung around the upper edge of the clasp 10 in the manner shown in Figure 2 for tightening the cam member 7 upon the bag material. If it is desired to remove a part of the contents of the bag, the bail 8 is released and the clasp is made to slide upwardly so as to uncover the lower end 15 of the slot 9, through which the tobacco may now be dispensed. As the contents of the bag grow less and less, the clasp is moved downward further and further, the prongs 13 automatically extending the depth of the slots 9. As the tongues 20 14 and 15 begin to project too far above the clasp for convenient handling, they may be cut off against the upper or lower edges 16 and 16' of the clasp. As far as they are retained, they will be accommodated by the bail 8 to lie flat against 25 the upper face of the clasp section 3 in the manner shown in Figure 2.

A much simpler form of my invention is shown in Figures 6 and 7, in which the clamping means is omitted and in which the clasp 17 is made to 30 have a fairly tight fit on the upper end of the Cellophane bag. In this form, a single prong 18 is provided to extend from one side of the clasp through the bag material to the other and to merely slit the bag material along a single line 35 as the clasp is made to move downward.

I claim:

1. A closure for a bag of the character described comprising a confining member slidable on the bag and means associated therewith for cutting 40 an aperture in the bag material when the member is moved from the open end of the bag toward the bottom thereof.

2. A closure for a bag of the character described, comprising a member surrounding the 45 bag and slidable thereon and having inwardly-projecting points for cutting the bag material when the member is moved from the open end of the bag toward the bottom thereof.

3. A closure for a bag of the character described 50 comprising a confining member slidable on the bag having means for cutting an aperture into the bag material when moved away from the open end of the bag, and having clamping means in advance of the cutting means for allowing the bag 55 to be closed against said aperture.

4. A bag of the character described having a 60 discharge slot in the wall thereof and having means movable thereon for covering and uncovering the slot including means for extending the

length of the slot when the first means is moved toward the bottom of the bag.

5. A bag of the character described having a discharge slot in the wall thereof and having a member movable thereon for covering and uncovering the slot, the said member having means for extending the length of the slot when the member is moved in a predetermined direction, and means for clamping the member upon the bag.

6. The combination with a bag, of a closure therefor comprising an elongated body member designed to enclose the walls of the bag and to hold them in abutting relation, and a looped handle pivotally carried at the ends of the elongated member and having a cam portion disposed in the member for clamping the bag thereto when the handle is in one position, and thereby sealing the bag.

7. A closure for a bag comprising two members connected at their ends and slidably receiving a bag therebetween, and a cutting means extending transversely between the members for slitting the bag as the closure is moved toward the bottom of the bag.

8. A closure for a bag comprising bag-clamping members secured to each other and designed to slidably receive a bag therebetween, and spaced cutting knives extending transversely between the members for cutting the bag when the closure is moved toward the bottom of the bag.

9. A closure for a bag comprising bag-clamping members secured to each other and designed to slidably receive a bag therebetween, and spaced cutting knives extending transversely between the members for cutting the bag when the closure is moved toward the bottom of the bag, a handle pivoted to the closure, and a bag-clamping means actuated by the swinging of the handle for preventing movement of the bag with respect to said first-named members.

10. A bag of "Cellophane" or the like having a slotted element thereon for pressing the side walls of the bag upon one another, the element being mounted with freedom of lengthwise adjustment on the bag so as to form a closure for the same adapted to follow the diminishing contents of the bag as the latter is emptied and one of the side walls of the bag having a discharge aperture adapted to be covered and uncovered by the element.

11. In combination, a bag of flexible material having an open end and having a discharge aperture in the side thereof and a closure movable on the bag for closing the open end, the closure being adapted to cover the side opening for closing the same.
